CONTAINER

Lloyd C. Fredrickson, Chicago, Ill., assignor to
 Abbott Laboratories, North Chicago, Ill., a corporation of Illinois

Application January 21, 1950, Serial No. 139,922

8 Claims. (Cl. 128—272)

1

My invention relates to dispensing containers and includes among its objects and advantages increased adaptability in use in containers of the type that are emptied by suspending them upside down.

In the accompanying drawings,

Figure 1 is a bottom view of a container according to the invention;

Figure 2 is a side elevation of the same container with the upper portion in section;

Figure 3 is a side elevation of the bottom portion only before suspension;

Figure 4 is a side elevation of the suspended bottle;

Figure 5 is a perspective of the bottom and of the container in shape to be suspended; and

Figure 6 is a plan view of a container with a modified fitting.

As shown in Figures 1 to 5 inclusive, a flask or bottle is provided with an annular groove 22 adjacent the bottom of the flask. The flask may be largely conventional such as a glass bottle for dispensing intravenous fluids, comprising a cylindrical barrel 10, a tapered portion 14, a neck portion 18 having means for attaching a cap or the like as by threads 20, and a concave bottom 16. A cup-shaped member 23 is of ductile metal, and fits over the bottom of the bottle. The lip 26 of the cup 23 is turned into the groove 22, thereby being more or less permanently attached to the bottom.

The cup-shaped member has two cut-out portions or apertures in the bottom 28 thereof. One aperture is the circular hole 30, and the other aperture is a concentric U-shaped hole 32. The remaining bottom portion between the two cut-out areas 30 and 32, forms a handle portion or bail 36. The straight sections 34 of the U-shaped aperture 32 diverge from the circular cut-out area 30 leaving extensions 38 of the bail 36, having increasing width as the divergence progressively becomes larger, and consequently of increasing strength as the divergence becomes larger.

The dispensing container is adapted to dispense the contents thereof from an inverted, more or less vertical, position. For suspending the dispensing container, the bail 36 is pulled up from its normal position in the plane of the bottom of the cup 28 to a position such as that shown in Figures 4 and 5. The enlarged bail portions 38 have increasing strength as the width of the section 38 increases, and as the bail 36 is pulled up the increasing strength of the enlarged section 38 causes a relatively large circular bend in

2

the portions 38, indicated in Figure 4, so that the bail is approximately axially aligned with the bottle. The axial alignment of the bail permits the container to be vertically suspended.

In the embodiment illustrated in Figure 6, the cup-shaped member 42 is attached to the bottle in the same way as the cup-shaped member 23, as indicated in Figure 2. The bail 44 is a tongue-shaped member having a circular aperture or eyelet 48 for suspending the bottle, and a shank portion 50 is of increasing width as the tongue approaches the rim of the cup. The increasing width section 50 functions similarly to sections 38, so that the increasing strength causes a large arcuate bend, whereby the tongue becomes axially aligned in pulled-up position.

In either construction it is possible to proportion the parts and the thickness of the metal, so that imposing the weight of the container and the contents on the bail 36 or the eyelet 48, will bend the supporting member into a position approximately coaxial with the bottle. Sometimes it is desired to hang the bottle against a wall, on a hook which projects outwardly less than the radius of the bottle, as for instance a door knob. Under such circumstances the user can greatly reduce the resultant tipping of the bottle, by pulling on the bail with a force several times as great as the bottle weight. Without injury to the bail, it is easy to change the curvature at 38 to a much shorter radius and have the bail offset from the axis of the bottle by an amount up to about one-third of the bottle radius. This is possible because the portions 38 and 50 are not only remote from the bottle axis and arranged on a line offset laterally on one side of a plane passing longitudinally through the bottle axis, but provide for hinge-like action on a line offset from the bottle axis.

Others may readily adapt the invention for use under various conditions of service by employing one or more of the novel features involved, or equivalents thereof. As at present advised with respect to the apparent scope of my invention, I desire to claim the following subject matter:

1. A dispensing container comprising: a bottle having an axis and a bottom substantially normal thereto; a sheet metal cup affixed to said bottle bottom; and a sheet metal bail defined by two apertures in the bottom of said cup; said bail being joined integrally to said cup at both its ends, at points radially spaced from the bottle axis; said joinings being arranged on a line offset

laterally on one side of a plane passing longitudinally through the bottle axis.

2. A dispensing container comprising: a bottle having an axis and a bottom substantially normal thereto; a sheet metal cup affixed to said bottle bottom; and a sheet metal bail defined by two apertures in the bottom of said cup; said bail being joined integrally to said cup at both its ends, at points radially spaced from the bottle axis; the bight of said bail being offset laterally to one side of a plane passing longitudinally through the bottle axis; said joinings being positioned to guide said bail, in approximately arcuate swinging movement, up and into said bottle axis and a substantial distance beyond the said axis, when said bail is pulled up to maximum height.

3. A dispensing container comprising: a bottle having a shallow annular groove adjacent the closed end thereof; and a ductile metal cup covering said closed end; the lip of said cup being turned into said groove to secure said cup on said bottle; the bottom of said cup having two apertures therein; one of said apertures being a circular opening; the other said aperture being a U-shaped opening, the arcuate portion thereof being concentric with said circular aperture; the portion of the cup bottom remaining between said apertures being available as a bail when pulled out at an angle from the plane of said bottom of said cup; the metal portions remaining between the straight sides of the said U-shaped aperture and said circular aperture having increasing width and increasing strength due to the divergence of said circular aperture and said straight sides, whereby outward displacement of said bail causes said metal portion to bend in relatively large arcs so that said bail is approximately axially aligned in vertical position.

4. A dispensing container comprising: a bottle having a shallow annular groove adjacent the closed end thereof; and a cup of ductile material affixed to the bottom of the bottle; a handle formed in the bottom of said cup by removing a circular portion therefrom and a concentric U-shaped section therefrom; said handle having enlarged portions between the divergence of the said U-shaped section and the said circular section, whereby the strength of the said enlarged portions is greater than the rest of said handle; said handle adapted to be raised at an angle from said cup bottom whereby said increased strength handle portions cause the handle to be axially aligned with said cup in vertical position; the lip of said cup being adapted to be turned into said groove on said bottle whereby said cup becomes attached to said bottle.

5. A dispensing container comprising: a bottle

having an axis and a bottom substantially normal thereto; a sheet metal cup affixed to said bottle bottom; a sheet metal eye member; and means for guiding said member from a position flat against said bottle bottom up into a plane parallel to the bottle axis; said guiding means comprising a flexible connecting portion of sheet metal joining said member and cup; said connecting portion joining said cup along a line parallel to said bottle bottom but offset laterally from a plane passing longitudinally through the bottle axis; said connecting portion decreasing progressively in bending strength, with a maximum where it joins said cup and a minimum where it joins said member.

6. A dispensing container comprising: a bottle having an axis and a bottom substantially normal thereto; a sheet metal cup affixed to said bottle bottom; a sheet metal eye member; and means for guiding said member from a position flat against said bottle bottom up into a plane parallel to the bottle axis; said guiding means comprising a flexible connecting portion of sheet metal joining said member and cup; said connecting portion joining said cup along a line parallel to said bottle bottom but offset laterally from a plane passing longitudinally through the bottle axis.

7. A dispensing container according to claim 6 in which said eye member defines a complete circle and said connecting portion is of greater dimensions than said eye member.

8. A container for therapeutic injectable solutions, comprising, in combination: a transparent bottle having a narrow peripheral groove adjacent the bottom thereof; and an end fitting comprising a metallic cup having annular axial engagement with the periphery of said bottom; the edge of said cup being turned into positive engagement in said groove; the bottom of said cup being slotted to define a curved bail adapted to be bent up, as around hinges at both ends of said bail; said hinges being in alignment with each other in a line lying near the transverse plane of said container bottom, and offset from a plane passing longitudinally through the axis of said container; said hinges being defined by integral metal portions of said cup where said bail merges at its ends with the body of the cup.
